UNITED STATES PATENT OFFICE.

WILLIAM S. HAYNES, OF BOSTON, MASSACHUSETTS, ASSIGNOR TO WM. S. HAYNES CO., OF BOSTON, MASSACHUSETTS, A CORPORATION OF MASSACHUSETTS.

THERMOCLARINET OR THE LIKE.

Application filed March 19, 1926. Serial No. 95,817.

This invention relates to wind instruments of the tubular type, such as clarinets, flutes, oboes and bassoons, and particularly to an arrangement whereby the temperature of the instrument barrel may be rapidly brought to substantially that of the room in which the instrument is to be played.

For the purposes of this application, I shall discuss my invention in its adaptation to the clarinet, although it is to be understood that such treatment is purely illustrative and in no way limiting. This instrument, particularly when made of metal, is quite sensitive to changes in temperature, and unless the temperature of the instrument is adjusted to that of the theater or other place where the instrument is to be played, the pitch will not be up to the proper standard. During cold weather, it is therefore customary for the artist to bring his instrument to the theater quite some time before he is scheduled to perform, in order that the instrument may become adjusted to the temperature of the theater. This not only results in the unnecessary loss of the artist's time, but where the outside temperature has been unusually cold, it sometimes results that the instrument has not been sufficiently adjusted to the theater temperature at the time of the performance, and hence the performance itself is apt to be unsatisfactory.

To obviate the necessity for this loss of time and to insure that the tonal qualities of the instrument will always be correct, I have devised my present invention. According to it, I arrange an outer tube over the barrel of the clarinet, which tube is sealed air-tight at its ends so that there is a dead air space between it and the barrel. When the artist is ready to perform upon the instrument he need only open the dead air space at its ends and expel the cold dead air contained within the tube, as by natural respiration repeated sufficiently to gradually warm the barrel of the instrument to approximately room temperature. This is only the work of a few moments and insures that the instrument will be in a satisfactory condition at the time of the performance.

The method of practicing my invention, together with an illustrative embodiment thereof showing a clarinet equipped in accordance with my general concept are described and illustrated in the accompanying specification and drawings, and the funda-

mental features of novelty particularly pointed out in the appended claims.

In the drawings:

Fig. 1 is an elevation, partly in section, of a clarinet equipped in accordance with my invention.

Fig. 2 is a cross section on the line 2—2 of Fig. 1, and

Fig. 3 is a detail view showing one of the valved vents for the enclosed air space.

I have indicated at 1 the mouthpiece, at 2 the barrel, and at 3 the bell of a clarinet of conventional type, the mouthpiece and bell being detachably connected to the ends of the barrel by the usual joints 4 and 5.

Sleeved about the barrel is a tube 6 which preferably extends from joint to joint thereof and defines with the barrel a dead air space 7 which is sealed at its ends by said joints 4 and 5. The barrel 2 is a flaring barrel, so that the air space gradually decreases in area as the bell end of the clarinet is approached. The usual tone hole defining flanges 8 are soldered, drawn or otherwise arranged upon the barrel 2 and extend through the air space 7 slightly beyond the outer face of the tube 6, said tube being apertured to receive said flanges.

In order to provide for expelling the dead air entrapped within said air space 7, the tube 6 is provided at either end with valved vent ports 9 and 10 which are adapted to be covered and uncovered by manually-operated hinged flap valves 11. The valves 11 are hinged at 12 in suitable bearings carried by the tube 6, and the valves are preferably spring pressed, as indicated at 13, so that normally they are held closed but may be opened manually, as by engaging the finger projections 14 carried by said valves and swinging them on their pivots against the action of the springs, the arrangement being such that the valves may be swung to a position in which they will remain open until definitely engaged and reclosed, as shown in dotted lines, Fig. 3.

With both valves open, the dead air contained within the air space 7 may be exhausted in any suitable manner, as for example by blowing through the upper vent opening 9, thereby expelling the dead air through the lower opening. This operation is repeated until the barrel is brought to substantially the temperature of the room in which the instrument is to be played. The artist may apply

his lips directly to the blow hole 9, or he may carry with him a short tube which he can insert in the blow hole for this purpose.

Although I have shown and described a construction in which the temperature of the barrel is adapted to be raised by natural respiration, it is obvious that other means for expelling the air contained within the dead air space 7 may be employed, the substance of my invention being the provision of such a space and its proper venting. Similarly, I may arrange in such space some means of artificially warming the barrel, as for example an electric resistance wire extending along the barrel and adapted to be connected with a suitable current source.

These and various other modifications in the construction and operation of my device may obviously be resorted to if within the limits of the appended claims.

What I therefore desire to secure by Letters Patent is:

1. The combination with the barrel of a tubular wind instrument, of means associated with said barrel constructed and arranged progressively to raise the barrel temperature.

2. The combination with the barrel of a tu-

bular wind instrument, of means associated with said barrel constructed and arranged to permit a circulation of warm air therewith whereby progressively to raise the temperature of said barrel.

3. The combination with the barrel of a tubular wind instrument, of a thermo-pneumatic attachment therefor constructed and arranged to permit the temperature of the barrel progressively to be raised.

4. The combination with the barrel of a tubular wind instrument, of a tube fitted over said barrel and defining therewith a dead air space, and means whereby the air within said space may be repeatedly exhausted and replaced by warmer air so as gradually to raise the barrel temperature.

5. The combination with the barrel of a tubular wind instrument, of a tube fitted over said barrel and defining therewith a closed air space having adjacent its ends valved vents adapted when open to permit repeated charges of warm air to be forced through said space whereby progressively to raise the temperature of said barrel.

In testimony whereof I affix my signature.
WM. S. HAYNES.
